UNITED STATES PATENT OFFICE.

MORRIS SELLERS, OF CHICAGO, ILLINOIS.

ROLLS.

SPECIFICATION forming part of Letters Patent No. 367,933, dated August 9, 1887.

Application filed January 24, 1887. Serial No. 225,346. (No model.)

To all whom it may concern:

Be it known that I, MORRIS SELLERS, residing at Chicago, in the county of Cook and State of Illinois, a citizen of the United States, have 5 invented or discovered a certain new and useful Improvement in Rolls, of which improvement the following is a specification.

In the accompanying drawings, which make part of this specification, Figure 1 is a view 10 in side elevation of portions of two rolls embodying my invention. Fig. 2 is a sectional view, the section being taken on the line *x x*, Fig. 1. Figs. 3 and 4 are views similar to Figs. 1 and 2 of a modified form of my invention.

15 In an application, D, of even date herewith, I have described and claimed a splice-bar comparatively thick at its middle portion, tapering therefrom each way toward its ends, and provided with seats for the bolt-heads or 20 nuts substantially parallel with the rear face of the bar, or the web of the rail to which said bar is to be applied.

The invention herein relates to the construction 25 of rolls suitable for the production of splice-bars having the characteristics above mentioned; and it consists, generally stated, of a roll having a tongue, a portion of whose operative surface is formed on the arc of a circle whose center is outside of the axis of the 30 roll, said portion of the tongue having certain sections or parts of its operative surface formed on arcs of circles concentric with the axis of the roll, and whose radii vary in accordance with the position of said sections, all as will 35 be more fully hereinafter described and claimed.

The roll 1 provided with the tongue 2, is cast and turned down in the usual manner, and, the tongue having been reduced to a diameter 40 equal to the greatest diameter in the finished roll, a portion, 3, of the face of said tongue is reduced or made to conform to the arc of a circle whose center is outside of the axis of the roll and distant therefrom an amount equal to 45 half the excess of thickness desired at the middle of the bar over that at its ends, all as more fully described and shown in applications A and B, of even date herewith.

The roll constructed as above stated is 50 adapted for the formation of a splice-bar comparatively thick at its middle and inclined or tapered on one face each way toward its ends.

In securing such a construction of splice-bar to the rails the fastening-bolts are bent by the tipping of the bolt-heads or nuts when the latter are screwed tightly against the face of the splice-bar, all as fully described in application D, of even date herewith. In order to avoid the bending of the bolts, I have described and claimed in said application a splice-bar 55 having seats for the bolt-heads or nuts parallel with the rear face of the splice-bar. For the purpose of forming the seats during the rolling of the splice-bar short sections or parts 4 of the operative face of the portion 3 of the 65 tongue 2 are made to conform as regards their faces to arcs of circles concentric with the axis of the roll, the radii of the arcs of circles varying in accordance with the position of the seat-forming sections 4 on the portion 3—*i. e.*, the 70 radii of the arcs of said circles increase in length proportionately to the distance of said seat-forming sections from the point *a* of least eccentricity of the portion 3 of the tongue. These seat-forming sections may either project 75 from the surface of the portion 3 of the tongue, as shown in Fig. 2, or be depressed below such surfaces, as shown in Fig. 3. The roll 5 is formed, in the usual manner, with a groove, 6, having its surface concentric with the axis of 80 the roll.

In using rolls constructed as above described a bar passing between said rolls will be reduced, as fully set forth in applications A and B, to a series of sections having comparatively 85 thick middle portions and tapering or inclined each way from such thick portions, the shaping of such sections being effected by the portion 3 of the tongue. In addition, however, to the tapering above referred to, the seat-forming sections 4 operate to reduce portions of the bar to parallelism with its rear face, either by depressing such portions of the bar when the construction of seat-forming sections shown in Fig. 2 is used, or the forcing of the metal 95 of the bar into the seat-forming depressions when the construction shown in Fig. 3 is employed. It is obvious that as the groove 6 of the roll 5 and the faces of the seat-forming sections 4 are concentric with the axes of rotation 100 of the rolls 1 and 5 the portions of the bar operated on by said parts will be substantially parallel. The number of seat-forming sections 4 corresponds to the number of bolts

to be used—*i. e.*, six or four, as circumstances require.

In case it is desired to form the splice-bar with ribs or a rib and flange along its edges, 5 grooves 7 are formed in the edges of the tongue, as fully described in application B, above referred to, and the seat-forming sections 4 inside the rib or flange forming grooves or recesses 7.

10 As the portion 3 of the tongue 2 and the seat-forming sections are not concentric, the divergence of the surfaces of said parts will be gradual at one end of said sections.

If desired, the tongue 2 may be formed with 15 two or more non-concentric portions 3 in the manner set forth in applications A and B, above referred to.

I claim herein as my invention—

1. In a mill for forming splice-bars having 20 their body portion tapering from the middle to their ends and provided with seats for bolt-heads or nuts, a roll having a tongue a portion of whose operative surface is formed on the arc of a circle whose center is without the 25 axis of the roll, said portion being provided with seat-forming sections formed on arcs of circles concentric with the axis of the roll, in combination with a roll having a groove concentric with its axis, substantially as set forth.

30 2. In a mill for forming splice-bars having their body portion tapering from the middle to the ends and provided with seats for bolt-

heads or nuts, a roll having a tongue a portion, 3, of whose operative surface is formed on the arc of a circle whose center is without the axis of the roll, said portion being provided with seat-forming sections formed on arcs of circles concentric with the axis of the roll, and whose radii are shorter than the radius of the portion 3, in combination with a roll 40 having a groove concentric with the axis of the roll, substantially as set forth.

3. In a mill for forming splice-bars having their body portion tapering from the middle to the ends and continuous upper and lower 45 edges, and provided with seats for the bolt-heads or nuts, a roll having a tongue a portion, 3, of whose operative surface is formed on the arc of a circle having its center outside the axis of the roll, said tongue being provided with grooves or recesses at its edges concentric with the axis of the roll and the portion of said tongue having seat-forming sections, also concentric with the axis of the roll, in combination with a roll having a groove 50 concentric with its axis, substantially as set forth.

In testimony whereof I have hereinunto set my hand.

MORRIS SELLERS.
